DESIGN FOR A CHAIR BACK

Viktor Schreckengost, Cleveland, Ohio, assignor
to The Murray-Ohio Manufacturing Company,
Cleveland, Ohio, a corporation of Ohio

Application March 22, 1940, Serial No. 91,300

Term of patent 7 years

To all whom it may concern:

Be it known that I, Viktor Schreckengost, a citizen of the United States, residing at Cleveland, county of Cuyahoga, State of Ohio, have invented a new, original, and ornamental Design for a Chair Back, of which the following is a specification, reference being had to the accompanying drawing, forming a part thereof.

Fig. 1 is a front elevational view of a chair back showing my new design;

Fig. 2 is a cross-sectional view thereof taken on the line 2—2 of Fig. 1;

Fig. 3 is a cross-section thereof taken on the line 3—3 of Fig. 1; and

Fig. 4 is a cross-section thereof taken on the line 4—4 of Fig. 1, and

Fig. 5 is a cross-section thereof taken on the line 5—5 of Fig. 1.

I claim:

The ornamental design for a chair back, substantially as shown.

VIKTOR SCHRECKENGOST.
